UNITED STATES PATENT OFFICE.

ISAAC C. POPPER, OF NEW YORK, N. Y.

FORMER AND FEEDER.

Application filed July 9, 1923. Serial No. 650,432.

My invention relates to an improvement in formers and feeders for semi-solid material such as butter, cheese and the like.

This present invention has been designed more particularly as a butter conveyor, and to go with the automatic butter cutter machine, set forth in Letters Patent No. 1,424,117, granted July 25, 1922.

In that machine, a former and screw-conveyor is used for forcing the material from the hopper to the cutting-wheel. The present invention represents a development of that general type of conveyor, and has been made in its present form in order to feed the material through the machine with uniformity and the required speed. Obviously it is applicable to the force feed of any material of plastic consistency such as butter, cheese, soap, yeast, and similar substances too numerous to mention.

In the accompanying drawings:

Fig. 1 is a side view of the screw conveyor; Fig. 2 is an end view of the same;

Fig. 3 is a side view of the former with parts broken away showing the screw;

Fig. 4 is a front end view of the former head;

Fig. 5 is a similar view of the plate for holding the wires for cutting the material into halves or quarters;

Fig. 6 is a rear view of the former;

Fig. 7 is a vertical section; and

Fig. 8 is a perspective of one of the adjustable blocks.

The numeral 1 represents the drive-shaft; 2 is a flange; and 3 is the screw which is of special design and construction as viewed in Figs. 1, 2 and 3 of the drawings. The outer or extreme end 4 is flat, free and unsupported, the entire support and rotation preferably being from the shaft 1 at the other end of the conveyor.

In the particular conveyor shown, there are three distinct spiral turns. The first turn 5 from the flat end 4, it will be observed, is of larger diameter and circumference than the other two turns 6 and 7.

The function of the flat free end 4 and of the larger turn 5 adjacent thereto is to create a continuous push and feed forward to the butter or other material, out through the forming-head of the machine.

In actual construction, the length of the

screw is approximately twelve and one-half (12½") inches; the diameter of the turn 5 approximately six (6") inches; of the intermediate turn 6 approximately four (4") inches; of the flange 2 approximately six (6") inches, and the space between the turns 5 and 6 is approximately six and one-half (6½") inches, whereas between the turns 6 and 7 the space is approximately four (4") inches.

While these dimensions may not be absolutely necessary, it has been found that a conveyor of these dimensions functions admirably in creating the even forward flow or movement of the material being fed, and in operation cooperates with the cutting machine to produce a machine of large and maximum capacity. With this conveyor, the output is limited only by the ability of the operator to feed material to the conveyor, as the latter takes care of it and pushes it on as fast as the material is fed into the machine.

The screw conveyor is located in a divided box 8 which has an opening 9 at the top through which the material is fed to the conveyor. Hinged bolts 9^a hold the upper and lower sections of the divided box 8 together.

The material issuing from the box 8 is given shape by a former especially devised for the purpose and it may be cut into two or four parts accordingly as the butter or other material is to be divided into half or quarter pounds when finally severed by the cutting machine to which material is fed.

The construction of a suitable type of former will now be described. A plate 10 preferably made of wood and faced at its edges with metal 11 has an orifice 12 at the center and notches 13 (of which there are four) at the opposite edges to receive the hinged bolts 14 which have wing nuts 15 on their ends by means of which the former is removably held on the ends of the box.

A pair of guide bars 16 are secured horizontally across the discharge end or nozzle 100 of the machine and two blocks 17 are slidably mounted therebetween and they are each adjusted by a screw 18 swivelled in a plate 19 and having a wing nut 20 by means of which the screw is turned to adjust the blocks 17 in and out to regulate the trans-

verse area and size of the material issuing from the machine.

A metal frame 21 is secured in place by screws 22 extending into the guide bars 16 5 on the end of the machine.

When it is desired to cut the material into half or quarter sizes, a plate 23 is secured in the frame 21 and wires 24 are held under tension across the orifice 25 therein by the 10 tension screws 26 which are controlled by wing nuts 27. The plate 23 when used is held in place by screws 28 and clamp nuts 29.

Other types of formers might be employed, and the one described is merely illustrative.

I claim:

1. A conveyor of the screw type having a plurality of turns increasing in diameter

and pitch toward the outer free end and terminating in a substantially flat outer end, the plane surface of said flat end being approximately at right angles to the axis of the screw conveyor for creating a continuous push and feed forward of the material conveyed. 20 25

2. A conveyor of the screw type supported at one end only and having a plurality of turns increasing in diameter and pitch toward the outer free end and terminating in a substantially flat outer end, the plane surface of said flat end being substantially at 30 35 right angles to the axis of the screw conveyor for creating a continuous push and feed forward of the material conveyed.

In testimony whereof I affix my signature.

ISAAC C. POPPER.
